UNITED STATES PATENT OFFICE.

EDWARD J. ALLHISER, OF PHILADELPHIA, PENNSYLVANIA.

APPARATUS FOR TREATING HIDES.

1,411,249.

Specification of Letters Patent.

Patented Apr. 4, 1922.

Application filed November 27, 1920. Serial No. 428,765.

To all whom it may concern:

Be it known that I, EDWARD J. ALLHISER, a citizen of the United States, and a resident of Philadelphia, in the county of Philadelphia and the State of Pennsylvania, have invented certain new and useful Improvements in an Apparatus for Treating Hides, of which the following is a specification.

10 This invention relates to a device for applying to the outer faces of hides a liquid solution, usually a sulphide, preparatory to dehairing. The object of the invention is the economical application of the solution, 15 avoiding unnecessary waste and also avoiding the applying of the solution to the inner side of the hide, which application not only results in a loss of a certain amount of the solution but is injurious to the hides so treated.

20 A further object of the invention is a device of this character in which two hides are placed face to face, bringing their inner sides together, and are then subjected to a 25 spray of the desired solution, a portion being sprayed from above on the uppermost hide and a portion from below on the outer or hairy face of the lower hide.

The invention also consists in the novel 30 features of construction hereinafter described, pointed out in the claim and shown in the accompanying drawings, in which:—

Figure 1 is an end elevation.

Figure 2 is a top plan view.

35 Figure 3 is a section on the line 3—3 of Fig. 2, a pair of hides being shown in place and a roller bearing being shown partly in section.

The apparatus employed by me comprises 40 a vat 1 adapted to contain the liquid with which the hides are to be treated. Over one side of this vat and forming a partial cover for it is placed a table 2, inclining downwardly toward the central longitudinal 45 line of the vat. A second and lower table 3, inclined in the same direction, is placed over the opposite side of the vat, with its lower edge spaced from the vat side so that any liquid running down the table 3 will drain 50 back into the vat.

Upper and lower feed rollers 4 and 5 are placed above the vat, the lower roller being arranged between the two tables. The upper roller is mounted in adjustable spring 55 pressed bearings of the usual type, as at 6. The rollers are driven by a pulley placed on an extended shaft portion of the upper roller, as at 7.

A pump 8 of any desired type is placed at one end of the vat and is connected to 60 the bottom of the vat by a supply pipe 9. Liquid is pumped from the vat into upper and lower feed pipes 10 and 11, perforated as at 13 along their opposing faces, so that they spray the outer hairy faces of the hides 65 as they pass between them. It will be understood that the hides are placed with their inner faces together and fed through the rollers and between the pipes 10 and 11, being introduced at the upper side and removed from table 3. The liquid dripping from the hides runs down the table and drains back into the vat, and is again pumped through the pipes and resprayed, so that there is no waste of liquid. While 70 I have described and shown the device as treating two hides at a time it will be understood that the vat and rollers may be of such length that more than one pair of hides can be run through at one time. 80

I do not desire to be limited to any particular form of pump or vat, as these can be altered without making any change in the invention.

What I claim is:—

85 A hide treating apparatus comprising a vat, two tables arranged above the vat spaced apart and inclining in the same general direction, feed rollers arranged between the tables, spray pipes arranged one above the other and perforated to discharge a liquid toward each other, and a pump adapted to draw liquid from said vat and discharge it through said pipes, one of said tables draining back into the vat. 90

95 In testimony whereof I affix my signature.

EDWARD J. ALLHISER.
